SEWING CABINET

Benjamin L. Franklin, Tucson, Ariz.

Application November 28, 1952, Serial No. 22,486

Term of patent 14 years

(Cl. D3—19)

To all whom it may concern:

Be it known that I, Benjamin L. Franklin, a citizen of the United States, residing at Tucson, in the county of Pima and State of Arizona, have invented a new, original, and ornamental Design for a Sewing Cabinet, of which the following is a specification; reference being had to the accompanying drawings, forming a part hereof.

Figure 1 is an isometric view of a sewing cabinet, showing my new design;

Figure 2 is a similar view taken from an opposite point of view;

Figure 3 is a sectional view taken along the line 3—3 of Figure 1; and

Figure 4 is an isometric view showing the cabinet in a partly opened position.

I claim:

The ornamental design for a sewing cabinet, as shown.

BENJAMIN L. FRANKLIN.
